UNITED STATES PATENT OFFICE.

GUSTAV H. STEUER, OF CHICAGO, ILLINOIS.

AUTOMATIC CLOSET-VALVE.

1,322,645.

Specification of Letters Patent. Patented Nov. 25, 1919.

Application filed November 26, 1915. Serial No. 63,526.

To all whom it may concern:

Be it known that I, GUSTAV H. STEUER, a citizen of the United States, and a resident of the city of Chicago, in the county of Cook and State of Illinois, have invented certain new and useful Improvements in Automatic Closet-Valves; and I do hereby declare that the following is a full, clear, and exact description of the same, reference being had 10 to the accompanying drawings, and to the numerals of reference marked thereon, which form a part of this specification.

This invention relates to an improved type of automatic flushing valve particularly 15 adapted for use with closets, though of course suitable for use in any other manner to which such type of valve is adapted. The valve embracing the principles of my invention is constructed to operate automatically 20 cally after a person has pressed inwardly on a small plunger to set the mechanisms of the valve in operation, the pressure of the water supply line in which said valve is connected serving to operate the mechanisms to permit 25 a predetermined quantity of water to flow through the valve, the valve thereafter returning automatically to normal or closed position, even though the plunger is still held depressed.

30 It is an object therefore of this invention to construct an improved type of closet flushing valve adapted to operate automatically by utilization of the pressure of the fluid supply line, the mechanisms being released 35 for operation by momentary pressure on a small plunger provided for the purpose, and thereafter operating automatically to permit a flow of fluid to take place through the valve for a period of time 40 dependent upon the adjustment of a controlling means provided for the purpose.

It is an object therefore of this invention to provide a flushing valve adapted when released for movement by momentary actuation 45 of a releasing element, to operate to open position under pressure of the fluid supply and remain open a predetermined time, then returning automatically to closed position.

It is also an object of this invention to 50 provide a flushing valve wherein a series of valves are provided opening in successive order to relieve pressure on one side of a relatively large piston which, by its movement, due to the change in pressure on the 55 different sides thereof, moves to open a main valve to admit a relatively large flow of

water therethrough, and with a by-pass passage serving according to adjustment of the controlling means for said by-pass, to again restore equal pressures on each side of said 60 piston to cause the same to move with its associated elements and main valve to initial position.

It is also an object of this invention to construct a flushing valve wherein a main 65 valve closure is provided forming a part of a piston, and with a series of auxiliary valves mounted on said main valve and piston adapted to open in successive order to relieve the pressure on one side of said piston whereby the same is actuated by the fluid pressure of the fluid supply to move and open said main valve, the same remaining open for a period of time determined by mechanism controlling the flow of fluid to 70 opposite sides of said piston whereby the pressures are again equalized, permitting said piston and associated main valve to move to initial position to shut off the flow. 75

It is furthermore an object of this invention to construct a flushing valve wherein a main valve forms a part of a piston which, when the parts are in normal or shut off position, is at rest with the fluid under the pressure of the supply line disposed on each side thereof, and provided with auxiliary valves adapted to be opened to permit release of the fluid on one side of said piston, causing the piston to move due to the pressure on the opposite surface 80 thereof to thereby open the main valve, said auxiliary valves closing after opening of the main valve and the main valve remaining open until pressures are again restored on the opposite surfaces of the piston through a by-pass passage provided for 85 the purpose.

It is furthermore an important object of this invention to construct a flushing valve adapted to be released for automatic 100 operation by momentary pressure upon an actuating plunger which serves to open auxiliary valves in successive order mounted in a main valve which is operated by a piston, said auxiliary valves serving 105 to release the pressure on one side of said piston whereby the same is moved under the pressure of the fluid supply to open the main valve, maintaining said main valve open until equalized pressures are again 110 restored on the opposite sides of said piston through a by-pass passage provided for

the purpose communicating with the chambers on opposite sides of said piston.

It is finally an object of this invention to construct an improved type of flushing valve operating automatically after manual release of auxiliary valves forming a part thereof, to permit a certain predetermined quantity of flow to take place and thereafter closing automatically to shut off the flow and with the parts returned to normal position ready for another release and actuating movement.

The invention (in a preferred form) is illustrated in the drawings and hereinafter more fully described.

In the drawings:

Figure 1 is a side elevation of a closet seat illustrating one form of adaptation of a device embodying the principles of my invention thereto.

Fig. 2 is a front elevation of the valve.

Fig. 3 is a central section therethrough on line 3—3 of Fig. 2, with parts shown in elevation.

Fig. 4 is a top plan view of the valve.

Fig. 5 is an enlarged sectional view similar to Fig. 3, illustrating the release movement of the auxiliary valves preliminary to opening of the main valve.

Fig. 6 is a view similar to Fig. 5, but showing the parts in open position to permit a flow to take place through the valve.

Fig. 7 is a bottom plan view of the retaining spider for the upper auxiliary valve in the device.

Fig. 8 is a detail section taken on line 8—8 of Fig. 7.

Fig. 9 is a central sectional view of the slideable ring valve member.

Fig. 10 is a section taken on line 10—10 of Fig. 9.

Fig. 11 is a top plan view of one of the tilting disks for actuating the auxiliary valves.

Fig. 12 is a detail section taken on line 12—12 of Fig. 3, with parts omitted and parts shown in elevation.

Fig. 13 is a fragmentary top plan view of the contact releasing means at the end of the actuating plunger of the device.

Fig. 14 is a central sectional view through a modified type of valve.

Fig. 15 is a front plan view of the screen inclosing one end of the inlet by-pass of the valve.

As shown in the drawings:

The valve consists of a main casing 1, formed with a boss 2, thereon, in which an inlet pipe 3, is threaded, and at its lower end provided with a boss 4, through which an outlet pipe 5, is connected by means of a union 6. A horizontal partition 7, is formed within the casing, dividing the same into an upper and lower compartment, the upper compartment being in communication with

the inlet pipe 3, and the lower compartment being in communication with the outlet pipe 5. A relatively large cover or cap 8, is threaded on the upper end of the casing 1, to close the same, and a packing ring 9, is recessed into said cap to bear upon the upper end of said casing to seal the same.

Slidably mounted within the upper chamber of the casing 1, is a piston 10, which has formed integrally therewith a hollow cylindrical portion 11, terminating at its lower end in a valve closure with an adjustable sleeve or ring 12, threaded thereon, and provided with a sealing or packing ring 13, recessed thereinto adapted to fit around an annular valve seat 14, projecting upwardly and integral with the partition 7. Said sealing or packing ring 13, is held associated with the valve closure 12, by a long cut away ring or sleeve 15, which is threaded in the interior integral portion 11, and acts to compress the inner margin of said packing ring to hold the same in place, the lower or cut away portion of said sleeve or ring 15, extending downwardly through said annular valve seat 14, and partition 7, when the parts are in closed position, as shown in Figs. 3 and 5. Threaded into the upper end of said piston 10, is a spider 16, which serves to retain a packing ring 17, positioned around an aperture extending centrally through said piston and communicating with the interior of said cylindrical portion 11. Seated upon said packing ring 17, adapted to close the central aperture through said piston, is a hollow mushroom type of valve 18, provided with small apertures 19, through the stem thereof communicating with the hollow interior of said valve. Slidably secured within the lower hollow stem 20 of said mushroom valve is a centrally apertured stem 20, of a disk 21, provided with apertures 22, therethrough, and a coiled compression spring 23, is seated on the upper surface of said disk and bears at its upper end against said piston to return said disk 21 to normal position.

Fitted slidably within the hollow interior of said inner stem 20, is the stem 24, of a small mushroom valve 25, adapted to seat upon a packing ring 26, recessed into the upper end of said mushroom valve 18, to close communication through the upper end of said mushroom valve 18, and the interior thereof. Disposed directly beneath the disk 21, is another similarly apertured disk 27, provided with a relatively long stem 28, extending downwardly through and beyond the lower end of said sleeve or ring valve element 15. An actuating plunger 125 to thrust or tilt the stem 28, to one side to start the valve in operation is provided, and consists of a stem 29, having secured on its inner end a downwardly depending casing 30, slidably mounted in the upper end of

which is a rectangular plunger 31, and coiled within said casing 30, is a compression spring 32, disposed about an axially disposed pin 33, within said casing acting 5 normally to impel said plunger upwardly into its limit of movement or against the inner end of said stem 29. Said stem 29, has formed on its other or outer end an enlarged head 34, with the word "Push" lettered thereon, said head being movable inwardly into an inclosing cylindrical cap 35, held attached to said main casing 1, by a union 36. Also held in position by said union 36, and threaded into said cap 35, is 10 an inner cup element 37, a peripheral flange on which is disposed between the end of the cap 35, and a packing ring 38, surrounding the aperture in said casing 1, through which said cup element extends. The stem 29, extends through a central aperture in the end of said cup member 37, and disposed there-around on the interior of said cup member is a layer of packing material 38^a, held compressed by a washer 39, against which one 15 end of a compression spring 40, bears, the other end of said compression spring seating in a circular groove provided in the head 34, so that said spring serves two purposes, namely, to compress and retain the packing material around the stem 29, and 20 also to resist inward movement of the plunger head 34, and stem 29, and to return the same to normal when the same is released.

Formed in the walls of the casing 1, in 25 the upper compartment is a by-pass passage 41^a, the upper end thereof opening into the chamber above the piston 10, and the lower end thereof communicating through a conical aperture with the chamber below said piston 10. The quantity of flow 30 through said by-pass 41^a, is regulated by a conical valve closure 42, threaded into a boss 43, formed on the side of the casing 1, the outer end of the stem of said valve closure being squared, as indicated by the reference numeral 44, to receive a suitable tool 35 engaged thereon, to thread said valve closure inwardly or outwardly to vary the area of opening through the conical aperture at the lower end of said passage 41^a. A washer 45, surrounds the stem of said conical valve 42, and pressed thereagainst and around the stem of the valve is a ring 40 of packing material 46, held compressed 45 therein by a gland 47, threaded interiorly into the boss 43. A rubber plug 48, is secured in the outer end of a cap 49, which 50 incloses the adjusting mechanisms for said conical valve and which is threaded on the exterior of the boss 43, affording a stop for the cover 50, of the closet seat of a closet bowl 51, with which the valve embodying the principles of my invention is connected.

A screen 52, is mounted over the entrance 55 to said conical aperture at the lower end of

said by-pass 41^a, to prevent sediment or other impurities admitted through the inlet pipe 3, gaining access to the regulating valve for said by-pass 41^a.

I have illustrated a modified form of my 70 invention in Fig. 14, wherein the operation and construction is substantially identical with the exception that a slightly different form of releasing mechanism to start the valve in operation is provided. As shown 75 in the modified form, in place of the stem 28, of the disk 27, of the prior construction, I use a disk 53, provided with a hollow stem 54, within which is a coiled compression spring 55, and a slideable plunger 56, limit- 80 ed in its downward movement under the impulse of said spring by a pin 57, fixed in the stem and extending through an elongated slot in said plunger. In place of the stem 29, I use a stem 58, mounted in the manner 85 described with reference to said stem 29, of the prior construction, but provided with an actuating handle 59, the inner end of said stem 58, bearing against the plunger 56, and adapted to thrust the same to one 90 side when said stem is thrust inwardly by the handle. The construction and operation of the modified form of device is otherwise identical with that of the previous construction described.

The operation is as follows:

The valve in normal or closed position is shown in Fig. 3, that is, with the main valve closure resting upon its seat 14, and the auxiliary valves 18 and 25, also in closed 100 position. With the parts in this position the fluid entering the casing 1, through the inlet pipe 3, fills the upper compartment above the partition 7, below and above the piston 10, the fluid gaining access to the chamber 105 above the piston through the by-pass 41^a. In order to actuate the valve to flush the closet, the plunger head 34, is thrust inwardly, thereby thrusting the stem 28, to one side, as clearly shown in Fig. 5, and tilting the 110 disk 27, and by such tilting movement elevating the disk 21, resting thereon. The initial elevating movement of said disk 21, is first transmitted to the stem 24, of the small auxiliary valve 25, elevating the same 115 from its seat to permit a flow of fluid through the interior of the mushroom valve 18, and outwardly through the passages 19, provided therein, and a continuous upward movement of said disk 21, next elevates the 120 mushroom valve 18, so that egress of the fluid in the compartment above the piston 10, is provided through both of the openings controlled by the respective valves 18 and 25. Due to the fact that the area of 125 opening of the respective openings controlled by the valves 18 and 25, is considerably greater than the area of the opening into the by-pass 41^a, controlled by the valve 42, the pressure above the piston is lowered, 130

and consequently, due to the pressure beneath the same, the piston moves upwardly in the casing, carrying the main valve closure 12, therewith. Of course the ring 5 or sleeve element 15, also moves upwardly, and a strong flow of fluid takes place through the cutaway portion of said element 15, and downwardly through the lower chamber of the casing 1, and into the dis- 10 charge pipe 5.

As the piston 10, moves upwardly, the stem 28, is elevated above the plunger 31, which serves to tilt the same to one side, and as a consequence, under the stress of the 15 compression spring 23, the disks 21 and 27, are brought to normal position and with a consequent closure of the respective auxiliary valves 18 and 25 by gravity. This, however, in no way interferes with the flow 20 of water through the device, inasmuch as the main valve closure 12, is elevated away from its seat.

When the flow has taken place for a sufficient length of time to lower the level of the 25 fluid in the compartment above the partition 7, so that the pressure on the opposite surfaces of the piston 10, tends to become equalized, said piston, with its associated elements, moves downwardly by gravity at 30 a rate determined by the quantity of fluid flowing past the regulating valve 42, and upwardly through the by-pass 41^a, into the chamber above the piston. In the event that during the operation of the valve, the 35 plunger head 34, has been maintained depressed, which is not essential of course for operation of the valve, the stem 28, descends upon the plunger 31, thrusting the same downwardly against the compression of its 40 spring 32, so that the closing operation of the valve is in no way hindered or interfered with. Upon release of the plunger head 34, of course the plunger springs outwardly under the impulse of its spring 40, 45 and to one side of the stem 28, whereupon the small plunger 31, is thrust upwardly by its spring 32, into a position to again contact and tilt the stem 28, upon another operation of the valve. Said small rec- 50 tangular plunger 31, is rotatable in its casing to present any one of its flat surfaces for contact with the stem 28, so that said plunger may be rotated around to compensate for wear.

55 The period of time the valve remains in open position is determined by the time required for the pressure to become equalized on each side of the piston 10, and this is governed by the quantity of fluid allowed 60 to flow through the by-pass 41^a, which is in turn controlled by the adjustment of the valve 42, therefor. When a closing of the valve member 10—11 takes place, the flow is gradually cut off by the sleeve 12, sliding 65 downwardly over the tapered valve seat 14,

so that possibility of hammering is obviated. By adjustment of said sleeve 12, the quantity of water allowed to flow into the bowl for refilling the same is determined, and may vary for different bowls—hence the desirability of making said sleeve adjustable. 70

I am aware that various details of construction may be varied through a wide range without departing from the principles of this invention, and I therefore do not 75 purpose limiting the patent granted otherwise than necessitated by the prior art.

I claim as my invention:

1. In a device of the class described, a main valve, a piston associated therewith, auxiliary valves mounted in said piston, a by pass affording communication between the chambers above and below said piston, mechanism for opening said auxiliary valves, said mechanism comprising spring 85 controlled means permitting said auxiliary valves to close regardless of the release of the opening mechanism.

2. A flushing valve comprising a casing having a plurality of chambers therein, a main valve, a piston movably connected thereto, a plurality of auxiliary valves in said piston, mechanism carried by said main valve for opening said valves, and means for returning said mechanism to normal thereby permitting the auxiliary valves to close by gravity regardless of the release of the opening mechanism. 95

3. In a device of the class described, a casing having chambers therein, a main 100 valve, a piston movable therewith, a plurality of relatively adjustable auxiliary valves, an oscillating and reciprocating disk mechanism movable with said main valve for unseating said valves and means for returning the disk mechanism to normal permitting said relatively adjustable valves to automatically close. 105

4. A flush valve comprising a casing, a valve seat therein, a main valve adapted to seat thereon, a piston in said casing dividing the casing into a plurality of chambers above said valve seat, a plurality of valves movable with said piston, a disk connected with said valves adapted to open the same, 110 a disk bearing against the first named disk adapted to operate the same to open the valves and mechanism for operating the disks. 115

5. In a device of the class described, a 120 casing, a valve seat therein, a main valve adapted to seat thereon, a piston in the casing dividing the same into a plurality of chambers, a passage connecting the chambers on each side of the piston, a plurality 125 of auxiliary valves in the piston adapted to release the pressure from one side thereof, a plurality of disks in said main valve adapted to open said auxiliary valves, and a spring returning said disks to normal per- 130

mitting the auxiliary valves to automatically close.

6. In a device of the class described, a casing, a valve seat therein, a valve adapted to seat thereon, a piston rigidly connected with said valve, auxiliary valves in the piston adapted to release pressure from one side thereof, a spring controlled disk, mechanism in the piston and extending below the 10 valve for opening the auxiliary valves, a vertical spring controlled plunger adapted to operate said mechanism, and means for actuating said plunger.

7. In a flush valve, a casing, a valve seat, 15 a valve therein, a piston movable with the valve, auxiliary valves movable with the piston and valve and movable independently thereof, mechanism movable with and independently of the piston and valve 20 for opening said auxiliary valves, a manually operated stem in said casing, and a spring controlled plunger mounted at right angles to said stem on the inner end thereof and adapted to be operated by said stem 25 to actuate said mechanism, said plunger per-

mitting the mechanism to return to normal independently of the release of the stem.

8. In a flush valve a casing, a valve therein, a piston connected to move with said valve, a plurality of auxiliary valves movable with and also independently of the piston and valve, a plurality of disks connected to unseat said auxiliary valves, means for returning the disks to normal, a stem provided with a head thereon, a housing secured on said stem, a plunger in the housing adapted to operate the disks when the stem is actuated, and means in the housing permitting the plunger to move independently of the stem to allow the disks and auxiliary valves to return to normal independently of the release of the stem. 30 35

In testimony whereof I have hereunto subscribed my name in the presence of two subscribing witnesses.

GUSTAV H. STEUER.
